UNITED STATES PATENT OFFICE.

STEPHEN L. BUCHANAN AND FRANK J. LYTTON, OF COEBURN, VIRGINIA.

JACK PROP.

Application filed July 17, 1922. Serial No. 575,705.

To all whom it may concern:

Be it known that we, STEPHEN L. BUCHANAN and FRANK J. LYTTON, citizens of the United States, residing at Coeburn, in the county of Wise and State of Virginia, have invented certain new and useful Improvements in Jack Props, of which the following is a specification.

This invention relates to adjustable mine props, and has for one of its objects to provide a device of this character including a stock member having means for quickly increasing its length to correspond to the location which it is to occupy and with additional and separate means for imparting a powerful longitudinal strain to rigidly support the device in position.

Another object of the invention is to provide a device of this character including a stock member having means for quickly increasing its length to correspond to the location which it is to occupy, and with additional and separate means for imparting a powerful longitudinal strain to rigidly support the device in position, and with means for holding the stock in its adjusted position.

With these and other objects in view the invention consists in certain novel features of construction as hereinafter shown and described and then specifically pointed out in the claims, and in the drawings illustrative of the preferred embodiment of the invention:

Figure 1 is a vertical elevation in section on the line 1—1 of Fig. 2.

Fig. 2 is a front elevation.

Fig. 3 is a section on the line 3—3 of Fig. 4.

Fig. 4 is a transverse section on the line 4—4 of Fig. 2.

Fig. 5 is a sectional detail of the lower portion of the device.

In operating coal mines when the cutting machine is to be located at the "face" of the gallery or the like, the miner is required to place at least two or more timbers or props under the "roof" as a precautionary measure, to insure the safety of the miner. The mining timbers thus employed are rather heavy and cumbersome and much time and labor is required to place them in position and to move them from place to place.

The principal object of the present invention is to provide an adjustable device to be employed in place of the ordinary mine tim-

ber or "jack props," and which may be quickly adapted to galleries or "drifts" of varying heights, and which may be repeatedly used or moved from place to place as required and without detaching any of the 60 parts.

The improved device comprises a hollow tubular supporting body including a rear portion 10, spaced side portions 11 and 12 and connected by a bottom or base portion 13 and with a shortened front portion 14 at the upper part, the latter coacting with the back 10 and sides 11 and 12 to form a tubular guideway to slidably receive a stock member 15.

At its upper end the stock member is provided with a bearing head 16 and is formed with gear teeth 17 in one side face and ratchet teeth 18 in another side face.

Formed in the inner face of the side portion 11 is an elongated pocket or seat 19 to receive a bar 20 having ratchet teeth 21 corresponding to and adapted to be engaged by the ratchet teeth 18 of the stock 15 when in one position as shown in Fig. 2, or withdrawn from engagement with the teeth of the stock when in another position, as shown in Fig. 3.

A spring 22 is disposed in the seat 19 and constantly engages the bar 20 to hold it 85 yieldably in its extended position with its teeth 20 in engagement with the teeth 18 of the stock and thus hold the stock in adjusted position.

A heavy wire U-shaped loop 23 engages 90 the bar 20 and extends through the side 11 of the support and is coupled at 24 to an operating lever 25 whereby the bar 20 may be moved bodily into its seat 19 against the resistance of the spring 22 and thus disconnect the teeth 21 of the bar from engagement with the teeth 18 of the stock and release the latter and permit it to fall by gravity into its lower position.

Extending through the sides 11 and 12 of the support is a shaft 26 carrying a gear wheel 27 in constant engagement with the teeth 17 of the stock and provided with a crank wheel 28 externally of the side member 12 to actuate the gear wheel, and thus rapidly move the stock 15 upwardly. Extending through the sides 11 and 12 of the support is another shaft or fulcrum member 29 on which a lever 30 is mounted to swing by a longitudinally directed slot 31. 110

The short end of the lever 30 is formed into a gear segment 32 adapted to engage the teeth 17 of the stock when the lever is in its inner position as shown in Fig. 1, and disconnected from the teeth when in outer position as shown in Fig. 5.

By this arrangement a strong leverage force may be imparted upwardly to the stock 15 a distance equal to the throw of the 10 lever, the adjusted position being held by the ratchet bar 20 until the lever can be released by drawing it outwardly the length of the slot 31 and again applied to the stock. Thus a step by step movement of this stock 15 may be accomplished to apply a strong longitudinal strain to the device to firmly hold it in position.

Thus in applying the device the crank wheel 28 is actuated to rapidly move the 20 stock upwardly to correspond to the distance between the floor and roof of the gallery, and the lever 30 then operated to forcibly "anchor" the device in place.

When the stock is to be released it is only 25 necessary to disconnect the lever 30 by drawing it outwardly, the length of its slot 31 and forcing the lower end of the small lever 25 inwardly to cause the withdrawal of the bar 20 and release the stock 15 which will 30 then fall by gravity into its lower position. The device can then be removed for use in another location, or stored for future use.

Attached to the face member 14 is a ring 33 to which a pull cable may be attached if 35 there be danger of the roof falling. In that event a cable is attached at one end to the ring 33 and the other end to a mine car at a safe distance, the miner having withdrawn to a position of the mine car when out of the 40 danger line. The car is then started and the improved prop pulled out from beneath the falling roof without danger to the operators.

The jack body on the sides 11 and 12 45 thereof, near the top or upper end of the same carries loop handles 34 which serve to permit the lifting of the jack in its entirety by hand when occasion requires. It is of course understood that these handles may be

of any desirable type and are fastened in 50 any manner to the body of the jack.

The improved device, which is technically called a "jack prop," can be constructed of any suitable material and of any suitable size and strength, and a number can be carried 55 on the motors of the mining cars and used as an emergency prop or timber in any part of the mine.

The preferred embodiment of the invention is disclosed in the drawings and set 60 forth in the specification, but it will be understood that modifications within the scope of the claimed invention may be made in the construction without departing from the principle of the invention or sacrificing any 65 of its advantages.

Having thus described the invention, what is claimed as new is:—

1. A mine prop comprising a tubular support, a stock provided with a bearing head 70 and movable in said support, said stock having gear teeth in one face and ratchet teeth in another face; a bar movable in said support and having ratchet teeth adapted to be engaged with the ratchet teeth of the stock, 75 an operating appliance carried by said support and engageable with the gear teeth of the stock, and means carried by said support for disengaging the bar from the stock.

2. A mine prop comprising a tubular support, a stock provided with a bearing head 80 and movable in said support, said stock having gear teeth in one face and ratchet teeth in another face, a bar movable in said support and having ratchet teeth adapted to be 85 engaged with the ratchet teeth of the stock, a gear wheel mounted in the support and engageable with the gears of the stock and operating to quickly actuate the stock, a lever pivoted in the support and having gear 90 teeth engageable with the gear teeth of the stock whereby a powerful lifting force may be applied to the stock.

In testimony whereof, we affix our signatures hereto.

STEPHEN L. BUCHANAN.
FRANK J. LYTTON.
